DESIGN FOR A BOOKSTAND

Pauline McCoy, Oakland, Calif.

Application June 30, 1934, Serial No. 52,406

Term of patent 14 years

To all whom it may concern:

Be it known that I, Pauline McCoy, a citizen of the United States, residing at Oakland, in the county of Alameda and State of California, have invented a new, original, and ornamental Design for a Bookstand, of which the following is a specification, reference being had to the accompanying drawing, forming part thereof.

Fig. 1 is a side elevation of the book stand, showing my new design.

Fig. 2 is a perspective view of the book stand.

I claim:

The ornamental design for a book stand, as shown.

PAULINE McCOY.
